CLAIM

The ornamental design for a mounting component of a pivoting flashlight mount, as shown and described.

DESCRIPTION

FIG. 1 is an isometric view of a mounting component of a pivoting flashlight mount according to the present disclosure;

FIG. 2 is another isometric view of the mounting component of a pivoting flashlight mount shown in FIG. 1;

FIG. 3 is a front elevational view of the mounting component of a pivoting flashlight mount shown in FIG. 1;

FIG. 4 is a right side elevational view of the mounting component of a pivoting flashlight mount shown in FIG. 1; FIG. 5 is a rear elevational view of the mounting component of a pivoting flashlight mount shown in FIG. 1;

FIG. 6 is a left side elevational view of the mounting component of a pivoting flashlight mount shown in FIG. 1; FIG. 7 is a top plan view of the mounting component of a pivoting flashlight mount shown in FIG. 1; and,

FIG. 8 is a bottom plan view of the mounting component of a pivoting flashlight mount shown in FIG. 1.

The broken lines shown in the Figures are included for the purpose of illustrating portions of the mounting component of a pivoting flashlight mount that form no part of the claimed design.
